CLAIM

I claim the ornamental design for a charging mount, as shown and described.

DESCRIPTION

FIG. 1 is a front perspective view of a charging mount according to the present invention;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines shown in the drawings illustrate portions of the charging mount that form no part of the claimed design.
